Inventor:

UNITED STATES PATENT OFFICE.

MARY KAVANAGH, OF NEW YORK, N. Y., ASSIGNOR TO THE BUTTERICK PUBLISHING COMPANY, (LIMITED,) OF SAME PLACE.

DESIGN FOR A MISS'S COSTUME.

SPECIFICATION forming part of Design No. 15,090, dated June 24, 1884.

Application filed May 12, 1884. Term of patent 3½ years.

To all whom it may concern:

Be it known that I, MARY KAVANAGH, of the city, county, and State of New York, have invented and produced a new and original 5 Design for a Pattern of a Miss's Costume, (numbered 9,206;) and I do hereby declare that the engraved prints accompanying this specification convey to any one accustomed to using paper patterns a clear understanding of how a 10 garment made up by the pattern will appear.

The design shows a round walking-skirt and an over-dress. The over-dress exhibits a closely-fitted front, displaying a wide cluster of tucks at the center above the waist-line, falling 15 in a point at each side below, and exhibiting draping plaits in each back edge, a closely-

fitting basque-back exhibiting a fastening from the neck to the waist-line, displaying under-folded plaits below the fastening and each side-back seam, and having the appearance of falling over a deep side-plaited drape- 20 ry; coat-sleeves, and a standing collar.

What claim I as my invention, and desire to secure by Letters Patent, is—

The design for a miss's costume, as shown 25 in the engraved prints accompanying this specification.

MARY KAVANAGH.
